UNITED STATES PATENT OFFICE.

ARTHUR M. BURNHAM, OF GARDINER, MAINE.

SNOW-PLOW.

SPECIFICATION forming part of Letters Patent No. 530,614, dated December 11, 1894.

Application filed April 17, 1894. Serial No. 507,902. (No model.)

To all whom it may concern:

Be it known that I, ARTHUR M. BURNHAM, a resident of Gardiner, in the county of Kennebec and State of Maine, have invented certain new and useful Improvements in Snow-Plows; and I do hereby declare the following to be a full, clear, and exact description of the invention, such as will enable others skilled in the art to which it appertains to make and use the same.

My invention relates to an improvement in snow plows,—the object of the invention being to produce a snow plow which shall be so constructed and arranged that it can be made to pass in a straight line through deep snow or drifts without removing the snow the full width of the road.

A further object is to so construct the device that it can be adjusted to either remove all the snow from the road bed in the line of travel of the plow, or to remove only a portion of the snow, leaving a portion of the snow on the road, the device being also arranged to smooth and press such snow as may be left on the road, in order to render the road good and smooth.

A further object is to produce a snow plow which shall be simple in construction, easy to operate and effectual, in every respect, in the performance of its functions.

With these objects in view the invention consists in certain novel features of construction and combinations and arrangements of parts as hereinafter set forth and pointed out in the claims.

In the accompanying drawings: Figure 1 is a perspective view illustrating my improvements. Fig. 2 is a sectional view. Fig. 3 is a view of a modification.

A represents the runners of my improved snow plow, connected together by means of cross bars *a*, *b*, *c*, the front cross bar *a* having a sharpened forward edge adapted to act as a cutter for hard snow or ice, and the rear cross bar *c* being preferably made wide and with a beveled lower face adapted to smooth and press snow left in the road by the plow. At their rear ends the runners *A*, *A*, are provided with standards *d*, *d*, to which the rear end of a platform *B* is pivotally connected, the rod or shaft *e* by means of which said parts are connected together passing through

the upper ends of the standards *d* and through the rear ends of flanges *f* projecting from the under face of the platform. These flanges 55 extend nearly the entire length of the platform and throughout their forward portion are beveled, as at *g*. The forward end of the platform is made V-shaped and its edge sharpened to constitute a cutter adapted to cut 60 hard snow or ice with which the device may come into contact.

On the platform *B*, a V-shaped plow *C* is located and adapted to move the snow, through which the device is passed, in opposite directions. The point *h* of the plow preferably terminates at a point rearwardly of the front end of the platform.

Draft irons *i* are secured to the forward ends of the runners, and to these draft irons, 70 the cross bar *i'*, to which the tongue *i''* is attached, is pivotally connected by means of suitable brackets *i'''*.

When the forward end of the platform is resting on the forward ends of the runners, 75 the cutting edge of said platform will be practically in line with the bottom of said runners, so that said cutting edge will engage the snow in close proximity to the road bed and cause the snow to pass onto the platform, 80 where it will be met by the plow *C*, by means of which it will be moved to opposite sides of the device.

It may sometimes be desired that a portion of the snow be left on the road bed, in which 85 case the forward or cutting end of the platform will be raised so that it will not be so closely in proximity to the road bed. To readily raise and lower the forward end of the platform, the devices now to be described 90 will be employed. The rear end of the platform is made with a slot *j* through which a lever *D* projects, said lever being pivoted between its ends to lugs projecting from the under face of the platform. To the lower end 95 of the lever *D*, a rod *D'* is pivotally connected, the other end of said rod being secured to a wedge *E*, the ends of which are disposed between the runners *A*, *A*, and the flanges *f* on the under face of the platform. It will be 100 seen that by operating the lever *D* the wedge *E* will be moved back or forth and in consequence thereof, the forward end of the platform will be raised or lowered.

My improved plow is capable of being operated with good results in making a path through deep snow, the forward end of the platform and the cross bar *a* serving to cut and break hard snow and ice and the plow *C* serving to remove the snow to opposite sides of the device. When the snow is not removed entirely from the road bed (in the path of the device), the beveled face of the rear cross bar *c* will serve to smooth and press such snow as is left on the road bed so as to make the road good and passable.

It may sometimes be desired that the device shall move the snow only to one side, in which case, the plow *C* will be displaced by an adjustable blade *C*³, shown in Fig. 3, and this construction may be made on a smaller scale and well adapted for removing snow from sidewalks.

Instead of the means hereinbefore described for raising and lowering the forward end of the platform *B*, a cam or a screw may be used, if desired. It is evident that my improved plow may be provided with wheels to run on a railroad track, if desired.

My improvements are very simple in construction, and effectual, in every respect, in the performance of their functions.

Various slight changes might be made in the details of construction of my invention without departing from the spirit thereof or limiting its scope and hence I do not wish to limit myself to the precise details of construction herein set forth, but,

Having fully described my invention, what I claim as new, and desire to secure by Letters Patent, is—

1. In a snow plow, the combination with runners having standards at or near the rear ends elevated above the runners, of a platform hinged to these standards and extending to the forward end of the plow, and means lo-

cated between the platform and runners for raising and lowering the platform, substantially as set forth.

2. In a snow plow, the combination with a pair of runners, a front cross-bar connecting these runners together, said cross-bar having a sharpened forward edge, and a rear cross-bar adapted to drag over and smooth out the snow remaining on the road-bed, of a platform hinged at its rear end to the runners, and means for raising and lowering the platform, substantially as set forth.

3. In a snow plow, the combination with runners, of a presser bar secured to said runners, a platform pivotally connected with said runners and having its forward end constructed to produce a cutter, a plow located on said platform and means for raising and lowering the forward end of said platform, substantially as set forth.

4. In a snow plow, the combination with a platform pivoted at one end, of a lever pivoted between its ends, and a wedge connected to said lever and adapted to cause the forward end of the platform to raise or lower when the lever is operated, substantially as set forth.

5. In a snow plow, the combination with runners and standards projecting upwardly from the rear ends thereof, of a platform pivotally connected at its rear end with said standards, a plow on said platform, a pivoted lever, a wedge located between said runners and platform and a rod connecting said wedge with the pivoted lever, substantially as set forth.

In testimony whereof I have signed this specification in the presence of two subscribing witnesses.

ARTHUR M. BURNHAM.
